UNITED STATES PATENT OFFICE.

ABRAHAM E. LINDY, OF WEBSTER, MASSACHUSETTS.

HAND SOAP.

No Drawing.

Application filed May 27, 1926. Serial No. 112,143.

This invention relates to a hand soap particularly designed for removing oils or greases. Such soaps are largely used by painters, mechanics, garage men, electricians and other workmen, and are of great utility for any person whose hands are soiled by paint or grease.

It is the general object of my invention to provide a hand soap of a new and improved composition, which is particularly effective and satisfactory for the purposes defined.

Many such soaps contain a sand-like or gritty substance which is effective in dislodging dirt or grease, but which has a tendency to irritate the skin.

Accordingly, it is a further object of my invention to provide a hand soap in which all such sand-like or gritty substances are omitted or replaced by other substances, without impairing the effectiveness of the composition.

The invention further relates more specifically to the provision of a hand soap of the novel and improved composition which will be hereinafter described and more particularly pointed out in the appended claims.

While the proportions of the several substances in my improved soap may be varied more or less without seriously altering the effectiveness of the compound, I find that a satisfactory formula for my improved soap is substantially as follows:

Per cent.

35	Soap (preferably in the form of dry chips)	10½
	Calcium carbonate precipitate	10
	Soda ash or sodium carbonate	3½
	Very fine wood saw-dust	2½
40	Sassafras or other perfume	½
	Water	73½
		100

45 It will be understood that the sassafras or other perfume is provided merely for giving a pleasant odor to the compound and that it has no particular function as a cleansing element.

The fine saw-dust gives body to the composition and also has a scouring effect similar to the gritty substances previously employed, but without producing any irritating effect upon the skin. The composition, when carefully made and having its parts thoroughly mixed and commingled, forms a thick paste, which if put up in tin boxes, will retain its moisture for a long time and will not become hardened or caked in the box.

The soda ash and calcium carbonate cooperate with the soap chips in producing an effective cleaning compound and in loosening and removing such substances as paint, grease or oil.

The hand soap composition above described may be easily manufactured at a reasonable cost and may be used indefinitely without injurious effects to the skin.

As previously stated, the exact proportions given in the formula may be substantially varied without destroying the efficiency of the soap in many respects. Accordingly, I do not wish to be limited to the exact details and proportions herein disclosed, otherwise than as set forth in the claims, but

What I claim is:

1. A hand soap consisting of substantially a one-tenth part of water-soluble soap, a one-tenth part of calcium carbonate precipitate, and small amounts of soda-ash and wood-sawdust, approximating one-third and one-fifth the proportion of soap, respectively, and remaining parts water sufficient to make a paste.

2. A hand soap consisting of approximately ten and half percent of water-soluble soap, ten percent of calcium carbonate precipitate, three and half percent of soda-ash, two and half percent of wood-sawdust, seventy-three and half percent of a mixture of water and perfume.

In testimony whereof I have hereunto affixed my signature.

ABRAHAM E. LINDY.
